(57) **CLAIM**

The ornamental design for a mobile hologram apparatus, as shown and described.

DESCRIPTION

The present application is a divisional of, claims priority to and the benefit of U.S. Patent Application Serial No. 29/569, 369, filed on Jun. 27, 2016, now U.S. Design Patent No. D858,614, the entirety of which is incorporated herein by reference.

FIG. 1 illustrates a top perspective view of an unassembled mobile hologram apparatus, according to a first embodiment.

FIG. 2 illustrates a top plan view of the unassembled mobile hologram apparatus, according to the first embodiment.

FIG. 3 illustrates a right-side view of the unassembled mobile hologram apparatus, according to the first embodiment.

FIG. 4 illustrates a left-side view of the unassembled mobile hologram apparatus, according to the first embodiment.

FIG. 5 illustrates a bottom plan view of the unassembled mobile hologram apparatus, according to the first embodiment.

FIG. 6 illustrates a rear view of the unassembled mobile hologram apparatus, according to the first embodiment.

FIG. 7 illustrates a front view of the unassembled mobile hologram apparatus, according to the first embodiment.

FIG. 8 illustrates a top perspective view of a folded assembled mobile hologram apparatus, according to a second embodiment.

FIG. 9 illustrates a top plan view of the folded assembled mobile hologram apparatus, according to the second embodiment.

FIG. 10 illustrates a right-side view of the folded assembled mobile hologram apparatus, according to the second embodiment.

FIG. 11 illustrates a left-side view of the folded assembled mobile hologram apparatus, according to the second embodiment.

(Continued)

FIG. 12 illustrates a bottom plan view of the folded assembled mobile hologram apparatus, according to the second embodiment.

FIG. 13 illustrates a rear view of the folded assembled mobile hologram apparatus, according to the second embodiment.

FIG. 14 illustrates a front view of the folded assembled mobile hologram apparatus, according to the second embodiment.

FIG. 15 illustrates a top perspective view of a folded assembled mobile hologram apparatus, according to a third embodiment.

FIG. 16 illustrates a top plan view of the folded assembled mobile hologram apparatus, according to the third embodiment.

FIG. 17 illustrates a right-side view of the folded assembled mobile hologram apparatus, according to the third embodiment.

FIG. 18 illustrates a left-side view of the folded assembled mobile hologram apparatus, according to the third embodiment.

FIG. 19 illustrates a bottom plan view of the folded assembled mobile hologram apparatus, according to the third embodiment.

FIG. 20 illustrates a rear view of the folded assembled mobile hologram apparatus, according to the third embodiment.

FIG. 21 illustrates a front view of the folded assembled mobile hologram apparatus, according to the third embodiment.

FIG. 22 illustrates a top perspective view of the folded assembled mobile hologram apparatus partially inserted into a direct-mail piece, according to the third embodiment; and, FIG. 23 illustrates a top perspective view of a partially-folded assembled mobile hologram apparatus, according to a fourth embodiment.

The broken line in the drawings is included for the purpose of illustrating portions and environmental elements of the mobile hologram apparatus and forms no part of the claimed design. Additionally, the mobile hologram apparatus is not limited to the scale shown herein.

1 Claim, 11 Drawing Sheets
